UNITED STATES PATENT OFFICE.

THEODORE HAVILAND, OF LIMOGES, FRANCE.

DESIGN FOR A PLATE.

44,566.

Specification for Design.

Patented Aug. 26, 1913.

Application filed March 7, 1913. Serial No. 752,768. Term of patent 7 years.

To all whom it may concern:

Be it known that I, THEODORE HAVILAND, a citizen of the United States, residing at Limoges, in the Republic of France, have invented a new, original, and ornamental Design for Plates, of which the following is a specification, reference being had to the accompanying drawing, forming a part thereof.

The drawing is a plan view of a plate showing my design.

I claim:

The ornamental design for a plate as shown.

THEODORE HAVILAND.

Witnesses:

S. CHAURIET,
H. NUREAY.
